US00D680111S

(12) **United States Design Patent**
Tang et al.

(10) **Patent No.:** US D680,111 S
(45) **Date of Patent:** ** Apr. 16, 2013

(54) **ELECTRONIC BOOK**

(71) Applicants: **Chiang-Kuo Tang**, New Taipei (TW);
Jun Yang, Shenzhen (CN); **Ning Zhang**,
Shenzhen (CN)

(72) Inventors: **Chiang-Kuo Tang**, New Taipei (TW);
Jun Yang, Shenzhen (CN); **Ning Zhang**,
Shenzhen (CN)

(73) Assignee: **Hon Hai Precision Industry Co., Ltd.**,
New Taipei (TW)

(**) Term: **14 Years**

(21) Appl. No.: **29/440,072**

(22) Filed: **Dec. 19, 2012**

(57) **CLAIM**

The ornamental design for an electronic book, as shown and described.

DESCRIPTION

FIG. 1 is a perspective view of an electronic book showing our new design;

FIG. 2 is a front elevational view of the electronic book of FIG. 1;

FIG. 3 is a rear elevational view of the electronic book of FIG. 1;

FIG. 4 is a left side elevational view of the electronic book of FIG. 1;

FIG. 5 is a right side elevational view of the electronic book of FIG. 1;

FIG. 6 is a top plan view of the electronic book of FIG. 1; and, FIG. 7 is a bottom plan view of the electronic book of FIG. 1. The broken lines shown in the drawings represent portions of the electronic book that form no part of the claimed design.

1 Claim, 7 Drawing Sheets
